ADVERTISING DISPLAY DEVICE

Joseph J. Sheridan, San Mateo, Calif.

Application August 10, 1951, Serial No. 241,304

3 Claims. (Cl. 40—126)

1

This invention relates to improvements in advertising display devices and has particular reference to the provision of an apparatus for which an advertising display is employed that visibly discloses a bottle of liquid and a receptacle for the liquid with the liquid continuously flowing from the bottle into the receptacle.

One of the principal objects of the invention is the provision in the receptacle, that has the characteristics of a beer glass, of a novel and unique trapping means that causes a continuous mass of bubbles or foam to arise to the surface of the liquid to thus simulate the exact condition that prevails when beer is poured from a bottle into a glass and to further embody in the liquid trapping medium, a definite structure for controlling the height of the "head" or "collar" formed in the liquid to prevent an overflow of the same.

An additional object of the invention is to provide means in certain of the liquid supply tanks for agitating the liquid to increase the bubbles or foam supply.

Another object of the invention is to employ in the tanks of the invention a supply of amber colored liquid, the liquid being so treated as to render the same saponaceous, and to employ motor driven pumping means for conveying the liquid to the bottle, and conduit means for conducting or returning the liquid received in the glass from the bottle to the source of the initial liquid supply, namely the tanks.

A still further object of the invention is the provision of an advertising display device of the character described that is simple in construction, positive in operation, economical to manufacture, strong, durable, highly efficient and serviceable in use, and highly attractive and entertaining in the respect that it is most mystifying relative to the manner in which the suds or foam are created, and which device will accordingly attract the attention of the observers who will mentally absorb the display advertising matter.

Other objects and advantages will be apparent during the course of the following description.

In the accompanying drawing forming a part of this specification and wherein for the purpose of illustration like numerals designate like parts throughout the same,

Fig. 1 is a fragmentary front elevational view of the advertising display device, and disclosing to advantage a bottle and a glass adjustably positioned in a frame and illustrating a product, such as beer, being poured into a glass from the

2

bottle with a head or collar of foam gathered in realistic form in the top portion of the glass.

Fig. 2 is a fragmentary rear elevational view of liquid holding tanks and the inlet and outlet tubes employed in the invention.

Fig. 3 is a top plan view, partly in section, of the bottle and glass and the liquid holding tanks forming a part of the present invention, with a portion of the frame and panel being shown in section.

Fig. 4 is a bracketed view illustrating in front and side elevation the beer glass, the bubble trapping means positioned in the same, and the relationship of the inlet and outlet tubes relative to the trap and the glass.

Fig. 5 is a perspective view of the trap construction employed in the glass, and

Fig. 6 is a perspective view of one of the liquid holding tanks utilized in the present invention, and

Fig. 7 is a perspective view of one of the semi-circular shields that is utilized in the invention.

In the present invention and in the accompanying drawings wherein for the purpose of illustration is shown the preferred embodiment of the invention, the numeral 7 indicates, as a whole, the housing of the display device, the said housing embodying in its construction an artistic base 8 on which is mounted an apertured frame 9 equipped with rearwardly extending side walls 10 and 11. The said walls are vertically slotted as at 12 to permit the insertion therein of a vertical panel 13 on which is displayed any suitable advertising slogan, as indicated by the numeral 14. It will be noted that the said panel is provided with spaced openings 15, 16 and 17.

The numeral 18 indicates a rearwardly extending board or shelf that is suitably connected to the frame and is adapted to support thereon the air-tight tanks of the present invention. Cross pieces 19 are connected to the bottom of the housing, underlie the same and serve to space the housing from any suitable support. Optionally the rear shelf may be eliminated and the tanks can be positioned on a table or like support 20 that is placed in proximity to the frame, and in the rear thereof, as disclosed to advantage in Fig. 3 of the drawing.

The three plastic tanks employed in the invention are herein defined as the pump holding tank A, a middle or reserve tank B, and an end or reserve tank C. Each tank is equipped with a detachable cover 21, 22 and 23 respectively, the covers having suitable openings therein to permit the passage therethrough of inlet and outlet

tubes to be hereinafter described. The said tanks hold a supply of amber colored liquid that is used in the display to simulate the color of beer, which liquid is treated with a specially prepared wetting agent to render the liquid saponaceous, the foam created being equivalent to the sudsing effect of modern detergents. It will be noted that the liquid holding tank A is of greater height than the substantially rectangular tanks B and C, to compensate for the rise in pressure in tanks B and C when the device is in operation and the foam is being formed. Tank A is of a taller type than tanks B and C. However, the base and top of tank A are the same dimensions as of tanks B and C.

The said tank A is adapted to house therein on the base thereof a pump 24 that serves as the pumping medium to dispense the liquid from said tank. Vertical rods 25, that penetrate the cover 21, are employed for the purpose of supporting 20 thereon at their upper ends an electric motor 26. The motor is provided with electrical conductors 27 that function as the media for supplying electrical energy to the motor 26. Extending from said motor to the pump is the motor shaft 27' that 25 likewise penetrates the cover 21 and functions to actuate the pump.

It will be noted that a pair of cross tubes 28, that lie on the same horizontal plane, are provided between the tank A and the tank B, and likewise tubes 29 and 29' function to connect the tank B with the tank C. The respective tubes also serve to initially establish the same level of liquid in all three tanks. Due to the arrangement of the cross tubes there is established a 30 means of communication between the tanks that permits a continuous passage of liquid from the tank C to the tank B, and thereafter to tank A during the cycle of the liquid pumping operation. The cycle of the foam in the tanks is confined to the tanks B and C, while the liquid is circulated throughout the entire tank apparatus.

The numeral 30 designates a container simulating a bottle of beer that is suitably secured in an adjusted angular position to the panel 13. Rubber tube 31' is secured at its upper end to the bottle and communicates with the interior thereof through plastic tube 31, and is secured at its lower end to the pump for the purpose of conveying the liquid in the tank A to the bottle 30 when the pump is operating. As disclosed to advantage in Fig. 4, the numeral 32 indicates a receptacle such as a beer glass, likewise suitably secured, in an adjusted angular position, to the panel 13. I will be noted that the mouth of the glass is positioned in proximity to the neck of the bottle, underlies the same and that the said glass, as disclosed in Figs. 1 and 2, is adapted to receive the liquid 32' that flows freely from the bottle.

In Figs. 1 and 2 I have illustrated to advantage a plastic outlet tube 33 that is interposed between and is connected to the glass 32 and the tank C by means of elongated rubber tube 33'. This tube is designated as the liquid return tube because it functions to retrieve the liquid from the glass to return or convey the same to the tank C. In each of the tanks B and C there is provided a diagonally positioned plastic baffle 34 and 35, each of which has side marginal notches 36 and 37 provided therein (see Fig. 6). The liquid that passes into the tank C first contacts the upper surface of the baffle 34 and by gravity passes to the lower portion of said tank. Bubbles then arise to the surface of the liquid in this tank and create sufficient pressure to thus return the same through 75

a return rubber tube 38', that is connected to the tank C and likewise to the glass 32 by means of plastic tube 38 adjacent the upper portion thereof. The notches 36 and 37 are utilized for the purpose of permitting the liquid to pass through the plates and then level off in the tanks B and C. It is to be noted that the baffles by their angular position relative to the tanks serve to create agitation and the formation of bubbles as the liquid passes downwardly over the baffles. Each of the baffles 34 and 35 is similarly mounted in the respective tanks B and C. For example, each of the baffles 34 is loosely mounted relative to the apertured rear wall, the side walls, and the base of the tank. The notches 36 and 37 accordingly are the only means for passage of the liquid through the baffle and a circulation of the liquid is effected in the tank below the baffle.

The numeral 39 designates an additional rubber tube that is connected at one end to the lid of the tank B, protrudes therethrough into the suds, and is joined at its opposite end, as at 40, to the suds return tube 38'. This unique arrangement allows for a rotation of the suds.

As disclosed to advantage in Figs. 4 and 5 of the drawing, I have devised a trap, indicated as a whole by the numeral 39'. This trap is made of plastic material and is suitably moulded or otherwise secured to the inside of the glass. The trap embodies in its construction a rear plate 40 and side wings 41 and 42 that are positioned at right angles to the rear plate. It will be noted that the vertical position of the wing 42 is between the holes provided in the glass for the insertion of the plastic outlet tube 33 and the suds return plastic tube 38 and further that the said holes are staggered relative to each other. By virtue of this arrangement at no time will the outflow of liquid reach the level of the inlet tube 38, which tube functions to permit the return of suds from the reserve tanks B and C. The side wing 41 of the trap device is of lesser height than the wing 42 so that excess suds may thus readily pass or carry over the top of said wing 41 with the outflow of liquid and then return to the reserve tank C through the medium of the tube 33. By the arrangement of the wings in the trap there is created an area of least resistance for the suds that enables the same to readily circulate and pass out through the outlet tube. The diminished height of the wing 41 and the relative height of the suds in the glass are proportionate.

As disclosed to advantage in Fig. 7, the numeral 43 indicates one of a pair of shields that is employed in the invention. Each shield is made of plastic and is of a semi-circular shape and is closed at its top and open at its bottom or base. The shield 43 is annealed to the left side apertured wall of tank C and is so positioned that it is slightly spaced from the bottom inner surface of the tank. Thus, the end of the lower tube 29 that extends into the tank C is semi-enclosed, and accordingly the liquid flowing from tank C into tank B must pass under the shield 43 at its lowest point and thence pass upwardly into the tank B and over the baffle 35. The liquid and excess bubbles will also pass through the upper tube 29'. The numeral 44 designates a shield of similar construction to the shield 43, which shield 44 semi-encloses the ends of the cross tubes 28 that extend into the tank B from tank A.

In practice, a predetermined amount of liquid and sudsing agent are placed in the respective tanks. After the level of the liquid has been

established equally in all three tanks through the method of the connection tubes 28, 29 and 29', current is then applied to the motor to actuate the pump 24. Liquid is then lifted into the bottle 39 through the medium of the rubber tube 31'. As the liquid rises in the bottle it soon reaches a level where it overflows into the glass 32 and by its natural downward flow creates some suds or foam. The liquid then rises in the glass to the level of the outlet tube 33 and is then conveyed therethrough to the tank C, next to the tank B and thence to tank A, creating a cycle of liquid flow from the glass, the respective tubes 28, 29 and 29' serving as a media for the passage of the liquid from tank C to tank B and thence to tank A.

To bring out the salient features of the invention it is well to stress the particular function of the bubbles formation features, and accordingly it is to be particularly noted that the liquid in tanks A, B and C must fall to a relatively low level before bubbles floating thereon could pass from tank B to tank A. It is also to be stated that the bubbles are practically nil at this point in tank B due to the function of the baffle 35 and the notches 36 and 37 that permit the liquid to circulate at these points only. The said baffle guides in an upwardly direction in tank B the liquid and excess bubbles coming through the upper tube 29' from the tank C, while the liquid passes through the lower tube 29 from tank C practically clear of bubbles. This clearance is due to the presence of shield 43 at its position in tank C over the inlet of the lower tube 29 in tank C. The baffle 34 in tank C also has a distinctive function, namely, it serves to direct the liquid and its complement of bubbles returning from the glass 32 through the medium of the outlet tube 33 to tank C, in a manner that will permit the bubbles to form in quantity at the top of the liquid in tank C, for bubbles will naturally rise to the surface of a liquid.

When an excess amount of bubbles is present in tank C, a pressure is created that can only be relieved by a definite means of escape. This escape medium is provided by the return rubber tube 38' that leads from the inner side of the cover 23 on tank C to the plastic tube 38 in glass 32.

It will be noted that the wings of the trap 39 mounted or otherwise secured to the inner surface of the glass 32 are positioned in such a manner relative thereto that they shield the outlet tube 33, and further it will be noted that since the top and bottom of the trap are open, liquid can readily flow from the glass 32 through the outlet tube 33.

It has been stated that the outlet tube 33 is in a lower horizontal plane, in glass 32, than the plane of the return tube 38. Accordingly, the level of the liquid in glass 32 is not permitted to the tank C other than through the tube 33. By virtue of this arrangement, bubbles returning from the tank C to the glass 32, do so because of the pressure created in tank C. When the bubbles reach the glass 32, through the medium of the return rubber tube 38' the said bubbles will float on the surface of the liquid in glass 32 and thus form the referred to "collar" or "head" in said glass and the bubbles will then rise to a predetermined level which is established by the lower wing 41 of the trap. The suds are then returned with the liquid to tank C through the medium of the outlet tube 33.

The joint action of the liquid flowing from the

bottle 38 into the glass 32 and thence into tank C through outlet tube 33 creates a quantity of suds sufficient to establish a pressure in tank C that becomes equalized by the passing of some of the bubbles or suds through the upper connection tube 29' into tank B.

When pressure in tank B becomes sufficient, the bubbles then pass upwardly through the tube 39 in the cover of tank B to join tube 38 from tank C by utilizing a plastic Y or T at the point 43. This action makes it possible for the suds to follow a given cycle, namely, from glass 32 to tanks C and B and back again to glass 32. The construction of the invention herein described permits the clear liquid to reach tank A and bottle 38, while confining all bubbles to the tanks B and C and the glass 32.

It is to be understood that the form of my invention herewith shown and described is to be taken as a preferred example of the same and that various changes relative to the shape, size, material and arrangement of parts may be resorted to without departing from the spirit of the invention or the scope of the subjoined claims.

Having thus described my invention, I claim:

1. In an advertising device the combination of an advertising surface, a liquid holding container in front of said surface, a receptacle in front of said surface and positioned below said container for receiving the liquid dispensed from the latter, means for supplying liquid to said container, a liquid trapping bubble forming member in said receptacle for agitating the liquid therein and to prevent an overflow of the bubbles in the receptacle said trapping member embodying in its construction a rear plate, and side wings positioned at right angles to said plate, one of said wings being of lesser height than the other wing, conduit means for draining a predetermined amount of the liquid from said receptacle to convey the liquid to the source of supply, and means in the source of supply for agitating the bubbles to create an additional bubble supply and to guide the bubbles upwardly from the source of the liquid supply to the receptacle.

2. In an advertising device the combination of an advertising surface, a receptacle in front of said surface, a container in front of said surface and mounted on said surface above said receptacle, a plurality of liquid holding tanks supported in the rear of said advertising surface and comprising an enlarged end tank, an intermediate reserve tank and an end reserve tank, cross-tubes interposed between said tanks to allow the liquid to circulate between the tanks, a motor driven pump in said enlarged tank, an inlet tube connected to said container and to said pump to convey the pumped liquid to said container to transfer the liquid to said receptacle, means in said receptacle for trapping the liquid therein to form a bubble supply and to prevent an overflow of bubbles from said receptacle, an outlet tube connected to said receptacle for conveying a supply of liquid from said receptacle to said end reserve tank, notched baffle means in said reserve tanks for agitating the liquid to create additional bubbles, tubular elements connected to said reserve tanks and to said receptacle for conveying additional bubbles to said receptacle, and a pair of shields, one in each reserve tank, and in proximity to said cross tubes, whereby only clear liquid is introduced into said enlarged end tank.

3. In an advertising device the combination

of an advertising surface, a liquid holding container in front of said surface, a receptacle in front of said surface and positioned below said container, a plurality of liquid holding tanks positioned in the rear of said surface, means interposed between the tanks to allow the liquid to circulate between the tanks, a motor driven pump in one of said tanks, an inlet tube connected to said container and to said pump to convey the pumped liquid to said container to transfer the liquid to said receptacle, means in said receptacle for trapping the liquid therein to form a bubble supply and to prevent an overflow of bubbles from said receptacle, an outlet tube connected to said receptacle for conveying a supply of liquid from said receptacle to one of

5 said tanks, baffle means in certain of said tanks for agitating the liquid to create additional bubbles, and tubular elements connected to certain of said tanks and to said receptacle for conveying additional bubbles to said receptacle.

JOSEPH J. SHERIDAN.
